Atty.

C. H. DREYER, OF NASHVILLE, TENNESSEE.

Letters Patent No. 83,051, dated October 13, 1868.

IMPROVEMENT IN PUMPS.

The Schedule referred to in these Letters Patent and making part of the same.

To all whom it may concern:

Be it known that I, C. H. DREYER, of Nashville, in the county of Davidson, and State of Tennessee, have invented new and useful Improvements in Pumps; and I do hereby declare that the following is a full, clear, and exact description thereof, which will enable those skilled in the art to make and use the same, reference being had to the accompanying drawings, forming part of this specification.

This invention relates to improvements in pumps, the object of which is to provide an improved double-acting pump.

It consists in the arrangement of the valves and passages in the stationary piston of a pump whose cylinder is movable.

Figure 1 represents a sectional elevation of my improved pump, the section of the plunger being taken on the line *x x* of fig. 3;

Figure 2 represents a section of the plunger, taken on the line *y y* of fig. 3;

Figure 3 represents a plan view of the cap of the piston; and

Figure 4 represents a plan view of the lower portion of the piston.

Similar letters of reference indicate corresponding parts.

A represents a cylinder, arranged to be reciprocated on the fixed hollow piston-rod *B*, and provided with a stuffing-box at each end.

Within the cylinder, the rod is provided with a fixed piston, constructed in two parts, *D* and *E*.

The lower face of the cap is chambered out at four equidistant points around the centre for the reception of the four valves, *a* *b* and *c* *d*, working on the face of the part *E*, two of which, *a* and *c*, alternately open and close communication with the lower portion of the piston-rod *F*, while *d* is arranged to govern the passage from the lower portion of the cylinder to the exhaust, and *b* the passage from the upper portion of the cylinder to the exhaust-portion *G* of the piston.

e and *f* represent passages from the valve-face of

the part *E* of the piston to the lower part of the cylinder, to conduct the water thereto when received through the valve *a*.

g, *h*, and *i*, represent passages through the upper part *D* of the valve, to conduct the water to the upper part of the cylinder when received through the valve *c*.

k and *l* represent passages leading through the top, *D*, of the piston, and communicating with corresponding chambers in the part *E*, leading to the space in the latter under the valve *b*.

According to this arrangement, when the cylinder is moved in a downward direction, the water will be drawn from the tube *F* under the valve *a*, which will be raised, and through the passages *e* and *f* into the lower portion of the said cylinder, while the water which is in the upper part of the cylinder will be forced down through the passages *k* and *l*, raising the valve *b*, and passing into the exhaust-tube *G*, and, when the cylinder is raised in an upward direction, the water will be raised through the valve *c*, and the passages *g h i*, into the upper portion, while the water in the lower part of the said cylinder will be forced up through the valve *d* and into the exhaust-tube *B*.

This arrangement admits of a very simple and cheap construction of the valves and passages, while it forms a very reliably-operating pump.

I claim as new, and desire to secure by Letters Patent—

The fixed piston *D E*, constructed of two parts, and provided with the valves *a* and *b*, *c* and *d*, and their passages *e f g*, and *h i*, leading to the lower and upper parts of the cylinder, and the passages *k l*, all substantially as and for the purpose described.

The above specification of my invention signed by me, this 18th day of August, 1868.

C. H. DREYER.
